CHARLES E. STOCKS, OF EL PASO, TEXAS

CLAMP

Application filed January 11, 1929. Serial No. 331,822.

The present invention relates to resilient article supporting clamps, which are formed from single blanks of material, and constructed in a manner to permit the clamps to be supported by arms forming part of a rotary rack, the invention residing in the construction as claimed.

In describing the invention in detail, reference will be had to the accompanying drawings wherein like characters denote like or corresponding parts throughout the several views, and in which:—

Figure 1 is an elevation of the invention, Figure 2 is a fragmentary view of one of the arms, showing a clamp thereon.

Figure 3 is a section on line 3—3 of Figure 2.

In these views, the numeral 1 indicates a counter or other support and 2 indicates a plurality of uprights, each of which is formed with a base 3 which is suitably attached to the support 1. Three-way couplings 4 are fastened to the upper ends of the uprights and braces 5 connect the uprights together by having their ends engaging the couplings, so that the uprights are firmly supported. These uprights and their braces may be formed of tubing.

A number of collars 6 are adjustably attached to each upright by the set screws 7 and a hub 8 is rotatably supported on the upright by each collar. Arm forming rods 9 are threaded into holes in the hub so that the arms radiate from the hub, and the outer end of each arm is threaded to receive a cap 10. Spring clamps, such as shown at 11, are slidably arranged on the arms for holding the articles to be supported by the arms, though if desired, articles, such as ties, can be folded over the arms. These clamps are so formed that an article held thereby can be removed therefrom by a simple jerk on the arm. Each clamp is formed from a single blank of material folded upon itself to provide an intermediate hollow tubular portion 12, and nor-

mally contacting converging jaws 11 which project from the tubular portion as clearly illustrated in Figures 2 and 3. The tubular portion is split but has its free longitudinal edges 13 normally substantially contacting 50 so as to close the tubular portion as illustrated. The material is slit along spaced parallel lines, and the separated portions of the material defined by these slits are extended from the jaws at opposite sides of the tubular portion, and terminates above the latter in spaced 55 relation to each other, forming finger engaging elements 11' whereby the jaws may be opened by pressing against the finger engaging elements when desired. 60

Thus it will be seen that I have provided a plurality of rotary members, each formed with a plurality of radiating arms for supporting articles so that the customer, by rotating the member, can bring the various 65 arms, with the articles thereon, to a point where he can inspect the same.

When shirts, union suits or the like are to be supported by the arms, a pair of clamps can be placed on the arm, with the clamps engaging the shoulders of the article, so that the article will be held in unfolded position 70 and thus it can be readily inspected by the customer.

By removing the caps 10, the clamps can be 75 placed on the arms or removed therefrom.

It is thought from the foregoing description that the advantages and novel features of the invention will be readily apparent.

It is to be understood that changes may be 80 made in the construction and in the combination and arrangement of the several parts, provided that such changes fall within the scope of the appended claim.

What I claim is:—

A resilient clamping member formed from a single blank of material folded upon itself to provide a split hollow tubular member of uniform diameter throughout its length, the free longitudinal edges of said tubular mem- 90

ber normally substantially contacting to close the tubular member, and extended to provide a pair of converging jaws co-extensive in length with the tubular member and having their free ends normally engaged, and finger-engaging extensions projecting from the jaws in the same plane therewith and terminating above the tubular member at opposite sides thereof.

10 In testimony whereof I affix my signature.
CHARLES E. STOCKS.
